CLAIM

The ornamental design for an electronic cigarette section, as
shown and described.

DESCRIPTION

FIG. 1 is a perspective view of an electronic cigarette
section;

FIG. 2 is a front view of the electronic cigarette section;

FIG. 3 is a rear view of the electronic cigarette section;

FIG. 4 is a left side view of the electronic cigarette section;

FIG. 5 is a right side view of the electronic cigarette section;

FIG. 6 is a top view of the electronic cigarette section; and,

FIG. 7 is a bottom view of the electronic cigarette section.

The evenly spaced broken lines in the drawings depict
portions of the electronic cigarette section that form no part
of the claimed design; the dash-dot-dash line represents a
boundary of the claimed design.
